TELLTALE

Harry A. Douglas, Bronson, Mich., assignor to
 Kingston Products Corporation, Kokomo, Ind.,
 a corporation of Indiana

Application June 21, 1937, Serial No. 149,528

6 Claims. (Cl. 177—329)

This invention relates generally to electric signalling devices and more particularly has to do with what is called a telltale device, and one object of the invention is to provide improved means whereby to mount the device on an instrument panel or other support.

More specifically one object of the invention is to provide a tubular housing formed to carry a lamp and contact means therefore at one extremity, and provided with a plurality of resilient members or fingers at the other extremity, at least some of the fingers being provided with a flange and a cam which are adapted to cooperate with the sides of the panel whereby to maintain the housing in a predetermined position thereon.

Another object is to provide a lens having a holder therefor which is provided with a number of resilient elongated projections, at least some of which are adapted to cooperate with the fingers provided on said housing in a manner whereby said lens may be detachably connected to said housing before or after the housing is snapped into place in the support, the resilient projections also acting upon said fingers so that the housing will be more firmly held in place upon said support.

A further object is to provide an arrangement in which a number of the resilient projections on the lens holder serve to exclude some of the light rays from the lamp from passing through the openings or slots between the fingers on the housing.

Many other objects and advantages of the invention will be apparent to those skilled in the art after considering the description hereinafter set forth in connection with the drawing annexed hereto.

Referring to the drawing:

Figure 1 is a side view in elevation of the telltale device assembled to an instrument panel;

Figure 2 is a bottom view, partly in section, taken substantially on line 2—2 of Figure 1;

Figure 3 is an enlarged section of a part of the arrangement in Figure 2, more clearly illustrating the manner in which the device is maintained in place on the instrument panel; and

Figure 4 is a section taken substantially on line 4—4 of Figure 2, clearly showing the relation of the resilient members and projections provided on the respective members of the device.

Referring to the drawing, numeral 1 represents an instrument panel or other support provided with a circular aperture 2, and it is through this aperture that the telltale device is adapted to be inserted from the front side of the panel.

As clearly shown, the housing forming a part of the telltale device is comprised of a relatively long cylindrical extremity 3, and a rather short but enlarged cylindrical extremity 4. Adjacent the junction between the extremities, there is provided in the extremity 3 a pair of bayonet slots 5, diametrically arranged, and these are adapted to receive a pair of bayonet pins 6 projecting from the base of the lamp 7. A contact means generally designated 8, is permanently secured to the free end of the extremity 3 and is insulated therefrom. The contact means is provided with means whereby to support an electrical conductor 9, which has a contact terminal 10 secured thereto; and a compressible helical spring 11, forming a part of the contact means, is adapted to urge the contact 10 into electrical engagement with the contact 12 provided on the base of the lamp. Thus, it is apparent that the extremity 3 provides a socket for a lamp, and carries the contact means 8.

Considering now the improved means whereby to detachably connect the device to the instrument panel 1, the extremity 4 of the housing is provided with a plurality of parallel slots or openings 13 which form a plurality of resilient members or fingers 14, preferably five in number and all of the same circumferential extent. Although it is not essential, each of the fingers 14 is preferably provided with an outwardly extending projection or bead 15 having an angular cam portion 16 formed thereon as most clearly shown in Figure 3. Each of the fingers 14 is also provided with an outwardly extending flange 17 which is adapted to abut the front side of the instrument panel. When the telltale device is inserted through the aperture 2 of the instrument panel 1, from the front side thereof, the flanges 17 abut the front side of the panel, and the cam portions 16 on the beads 15 engage the rear arris or marginal edge of the aperture 2, and since the fingers 14 are resilient, the fingers are placed under tension and expand sufficiently to resiliently retain the device in a predetermined position with respect to the panel. In effect the cams 16 and flanges 17 substantially provide V-shaped seats adapted to receive the margins of the aperture in the panel, and the flanges 17 are pressed against the front side of the panel. It is to be here noted that the cam portions 16 are of such a character that they will act and hold the telltale device with respect to panels or supports in which the thickness thereof varies.

A lens 18 preferably concavo-convex in form to receive a portion of the lamp bulb, is adapted to

be carried by the housing, and as here shown, the lens is mounted in a lens holder 20. The lens holder is of such a character that a portion thereof is adapted to engage the front side of the instrument panel, and receive but not engage the flanges 17 provided on the fingers 14. This holder 20 is provided with a plurality of outwardly extending elongated projections 21, preferably six in number and of the same circumferential extent, but of less circumferential extent than that of fingers 14. A detent 22 is preferably provided adjacent the free end of each of the projections 21, and these are adapted to cooperate with the inner sides of the fingers 14. Although it is not essential it is preferable that at least some of the fingers normally assume a cocked position before they are inserted in the extremity 4, and these elongated projections function to detachably retain the lens in relation to the extremity 4 of the housing, and also act to spread apart the fingers 14 in order to more firmly hold the housing in place. Obviously, the lens may be inserted into the housing before or after the latter is connected to the instrument panel, and it is to be noted that at least one or more of the elongated resilient projections 21 on the lens holder overlie at least one or more of the slots 13 to exclude some of the rays of light from the lamp from passing through the longitudinal slots or openings 13 provided in the extremity 4. As clearly shown in the drawing, the projections 21 are preferably made so that the circumferential extent of each is greater than the width of any of the slots 13.

It is thus evident that the invention is directed to improved means whereby a telltale device and other devices embodying the invention may be detachably secured to an instrument panel or other support, and that the telltale housing is provided with a plurality of resilient fingers which cooperate with the margin of the aperture in the panel in a manner to maintain the housing in a predetermined position with respect thereto, that the elongated projections on the lens holder serve to detachably connect the lens with respect to the housing, and provide additional forces acting upon the resilient fingers provided on the housing in order to more firmly hold the housing in said predetermined position.

Having thus described my invention, it is obvious that various immaterial modifications may be made in the same without departing from the spirit of the invention; and therefore, I do not wish to be understood as limiting myself to the exact form, construction, arrangement, and combination of parts, herein shown and described.

What I claim and desire to secure by Letters Patent is:

1. In a device of the kind described, a relatively thin support provided with an aperture, a tubular housing extending through said aperture

and provided with a plurality of integral resilient fingers, and a lens holder provided with resilient elongated projections cooperating with said resilient fingers whereby to hold said holder in relation to said housing and press said fingers against the margins of said aperture to hold said housing in a predetermined position with respect to said support.

2. A support provided with a circular aperture, a tubular housing provided with a plurality of resilient fingers, each of said fingers being provided with a flange abutting one side of the support and a cam spaced apart from said flange cooperating with the other side of said support whereby to resiliently retain said housing in a predetermined position on said support, and resilient means movable transversely to the axis of said aperture cooperating with at least some of the fingers on said housing acting to expand same.

3. A device of the kind described, a support provided with an aperture, a housing extending through said aperture, a lamp and contact means carried by said housing, a plurality of fingers provided adjacent one extremity of said housing, at least some of said fingers being provided with a flange and a cam respectively abutting the front and rear sides of said support, and a lens having a holder provided with radially movable means cooperating with and acting upon at least some of said fingers whereby to detachably hold said lens in place and assist in maintaining said housing in a predetermined position on said support.

4. In a device of the kind described, a tubular housing provided with a plurality of spaced apart resilient fingers, a lens holder provided with resilient projections adapted to cooperate with said fingers to urge same outwardly.

5. In a device of the kind described and in combination, a support provided with an aperture, a housing extending through said aperture provided with a plurality of spaced apart resilient fingers, spaced apart portions provided on at least two of said fingers cooperating with the respective sides of said support, and detachable resilient means cooperating with said fingers adapted to urge said fingers outwardly whereby to better hold the housing in place in said aperture.

6. In a device of the kind described a support provided with an aperture, a tubular housing extending through said aperture provided with a plurality of spaced apart fingers, spaced apart portions provided on at least two of said fingers to substantially form V-shaped seats adapted to receive the margins of said aperture, and a lens holder provided with resilient means of a greater width than the width of the spaces between said fingers adapted to cooperate with and act upon at least two of said fingers in a manner whereby to better hold the housing in place and cover some of the spaces between said resilient fingers.

HARRY A. DOUGLAS.
